UNITED STATES PATENT OFFICE.

BENJAMIN G. GILBOUGH, OF CHICAGO, ILLINOIS.

SPARKING DEVICE.

No. 875,907.

Specification of Letters Patent.

Patented Jan. 7, 1908.

Application filed December 26, 1906. Serial No. 349,554.

To all whom it may concern:

Be it known that I, BENJAMIN G. GILBOUGH, a citizen of the United States, residing at Chicago, in the county of Cook and 5 State of Illinois, have invented a new and useful Improvement in Sparking Devices, of which the following is a specification.

My invention relates particularly to ignition devices in which the spark-plug, adapted 10 for connection with an engine-cylinder, is provided with a gas-actuated piston which serves in the actuation of the movable contact-member, or electrode, of the spark-plug.

My primary object is to provide a construction adapted to prevent undue heating 15 of the plug and one in which the necessary springs employed will be protected against undue heating and against undue deterioration, such as would come from operating 20 under other improper conditions.

Additional objects of the invention will appear from the description which follows.

The invention is illustrated in its preferred embodiment in the accompanying drawings, 25 in which—

Figure 1 represents an elevational view of my improved sparking device applied to an engine-cylinder, a fragmentary sectional view of the engine-cylinder being shown; 30 Fig. 2, a sectional view of the sparking device, the section being viewed in the same direction as in Fig. 1; Fig. 3, a similar section showing the gas-actuated piston of the spark-plug partially raised; Fig. 4, a similar 35 section showing the position of the parts just prior to the release of the electrode-actuating means from the piston; Fig. 5, a similar section showing the position of the parts immediately after the release of the electrode- 40 actuating means from the piston, while the piston is at the extreme outer end of its traverse; Fig. 6, a plan view of the device; Fig. 7, a perspective view of a spring-equipped piston-retracting rock-arm; and 45 Fig. 8, a broken section taken as indicated at line 8 of Fig. 5.

In the construction shown, A represents an engine-cylinder; B, a tubular plug having screw connection with the engine-cylinder, 50 and having a tubular stem b extending into the engine-cylinder and equipped with a point b¹, thereby constituting a fixed electrode; B¹, a vibratory electrode extending through the bore b² of the tubular plug and 55 having its outer end projecting beyond the

outer end of the tubular plug B; C, a disk insulatingly connected with the outer end of the tubular plug and equipped near one edge with a cylinder C¹, whose inner end communicates through a port c with the bore b²; 60 C²; a gas-actuated piston movable in the cylinder C¹ and having a reduced outer end c¹ extending through the outer end-cap c² of said cylinder; D, a standard supported on the disk C opposite the cylinder C¹ and separated from said cylinder by a space D¹ into which the outer end of the vibratory electrode B¹ extends; D², a rock-arm supported on the standard D and equipped with an adjustable electrode-actuating member D³; D⁴, 65 a pawl connected with the free end of the rock-arm D² and serving in the actuation of the same; and D⁵, a lever having a pivotal portion d passing through the standard D and pivotally supporting the rock-arm D², 70 and having an arm d¹ at substantially right angles to the pivotal portion d and equipped with a laterally projecting arm d² bearing against the outer end of the piston-stem c¹. 75

The disk C is provided with an opening c³ 80 through which the vibratory electrode B¹ projects and at said opening at the inner surface of the disk is provided a part-spherical seat or bearing c⁴ which receives a part-spherical bearing c⁵ with which the vibratory electrode is provided, said electrode having a stem c⁶ extending through the opening c³ and into the space D¹ between the standard D and the cylinder C¹. The stem c⁶ is provided with a stud c⁷ between which and the disk C is 85 confined a coil-spring c⁸ which encircles the stem c⁶, the spring serving to hold the bearing c⁵ in close contact with the seat c⁴. The upper end of the stem c⁶ is formed with a cam-surface c⁹ and projects through a slot c¹⁰ 90 in the member D³. One wall c¹¹ of said slot coacts with the cam-surface c⁹, serving to maintain the vibratory electrode normally 95 in an open position, as shown in Fig. 2.

The member D³ is clampingly secured to 100 the lower surface of the arm D² by a bolt d³ which extends through a perforation in the arm d² and through a slot d⁴ in the member D³, thus permitting adjustment of the member D³ laterally with relation to the stem c⁶ 105 of the vibratory electrode B¹. The member D³ is provided with an inturned arm d⁵ between which and the stem c⁶ is confined a leaf spring d⁶. The standard D is bifurcated, affording a slot in which the pivotal end of 110

the rock-arm D² is received, and in which the member D³ and the spring d⁶ are received. The free end of the rock-arm D² is provided with a shoulder d⁷ which rests normally 5 against the outer surface of the end-cap c² of the cylinder C¹. The stem c⁶ of the vibratory electrode is provided with a series of notches d⁸ which serve for adjustment of the spring d⁶. The spring d⁶ tends not only to 10 hold the vibratory electrode in the closed condition shown in Fig. 3, but tends also to depress the inner end of the rock-arm D² to the normal position of rest shown in Fig. 2. The pawl D⁴ is received by a slot d⁹ with 15 which the rock-arm D² is provided, and is supported on a pivot d¹⁰. The inner end of the pawl (end toward the engine-cylinder) is provided with a slightly curved surface d¹¹ which coacts with a part-spherical surface 20 d¹² with which the end of the stem c¹ of the piston C² is provided. The outer end of the pawl D⁴ is connected by a spring d¹³ with a lug d¹⁴ carried by the rock-arm D². The arm d² of the lever D⁵ bears against one lateral 25 edge of the pawl D⁴, serving to limit the turning movement of the pawl on its pivot. Said lateral edge of the pawl is curved as indicated at d¹⁵ to permit the parts to assume the relative position shown in Fig. 5.

30 The outer end of the piston C² is provided with a tapering, or frusto-conical, surface c¹², and the inner surface of the end-cap c² is provided at the perforation through which the stem c¹ projects, with a coacting conical 35 surface c¹³. When the piston is at the outer end of its traverse, the conical surfaces are brought together, as illustrated in Fig. 5, thereby tending to prevent escape of gas. The port c may be varied by means of a valve 40 c¹⁴ whose stem c¹⁵ has screw connection with the disk C, said stem projecting laterally beyond the edge of the disk, the projecting end being equipped with an operating wheel c¹⁶. The arm d² of the lever D⁵ is connected by a 45 spring E with a lug e carried by the disk C. Said arm d² is provided with a series of notches e¹, and the outer end of the spring E has a hook adapted to engage any one of said notches, thus providing for a variation 50 of the pressure exerted upon the piston through the medium of the lever D⁵. I have shown an oiling device F connected with the cylinder C¹.

55 A battery G in a circuit G¹ serves to produce a primary spark. One terminal of the circuit is connected with the standard D by a device G², and another terminal of the circuit is connected with the engine-cylinder and thus with the tubular plug B. The circuit is completed, of course, when the vibratory electrode is in contact with the stationary electrode.

60 The disk C is shown separated from the plug B by insulating material h, and the disk 65 is connected with the head of the plug B by

means of bolts h¹ which pass through insulating washers and sleeves h², as shown in Fig. 8. The details of connection are unimportant.

From the foregoing description, the operation of the device will be readily understood. The parts of the device are normally in the position shown in Figs. 1 and 2, with the vibratory electrode separated from the stationary electrode and the electric circuit broken. 70 When the compression in the engine-cylinder reaches a predetermined amount, the piston C² is moved by gas passing through the port c and overcoming the tension of the spring E¹. Normally, the pawl D⁴ rests upon the outer 75 end of the piston-stem c¹, and as the piston is forced outwardly, the rock-arm D² is raised through the medium of said pawl, thereby withdrawing the shoulder c¹¹ from the prominent portion of the cam c⁶ and permitting the 80 spring d⁶ to actuate the vibratory electrode B¹ and close the circuit. When the piston reaches the outer end of its traverse the pawl D⁴ (whose movement is restrained by the lever D⁵) slips off the end of the piston stem 85 c¹, thus permitting the rock-arm D² to drop to its original position with the shoulder d⁷ resting on the outer surface of the cylinder-cap c². In the return movement of the rock-arm D², the shoulder c¹¹ working on the cam 90 c⁶ actuates the vibratory electrode to break the circuit and cause a spark. By means of the manually adjustable valve c¹⁴, the passage of gas to the cylinder C¹ may be regulated, so that only a sufficient amount of gas 95 need be admitted to serve in the actuation of the piston, whereby undue heating of the parts may be obviated. Moreover, the springs employed in the construction are everywhere exposed to the atmosphere, reducing the tendency of injury to the springs. Furthermore, the springs are so arranged 100 that the movements are slight, so that notwithstanding the large number of operations which the device is called upon to perform, the life of the springs is long. I preferably provide the stem of the piston with a perforation k whereat an implement may be inserted for the purpose of loosening the piston in the event that it may become necessary 105 after long idleness of the device.

110 It may be remarked that inasmuch as a primary circuit is employed for producing a spark in a device of this character, a small current will serve to produce a large spark, though of low potential. Inasmuch as the volume of the spark is the desirable thing, it is obvious that sparking devices of the character herein disclosed possess an important 115 advantage over sparking devices employing an induced current to create the spark. Moreover, the improved device may be employed without use of a cam for making and breaking the circuit externally, thus obviating 120 the many objections incident to the use 125 130

of such an external make and break device, as well as greatly cheapening the cost of construction.

The foregoing detailed description has 5 been given for clearness of understanding only, and no undue limitation is to be understood therefrom.

What I regard as new, and desire to secure by Letters Patent, is—

- 10 1. In a sparking-device, the combination of a tubular plug adapted for connection with an engine-cylinder, a cylinder mounted thereon and in communication with said plug, a piston movable in said cylinder and having a stem projecting beyond the outer end of the cylinder, a vibratory electrode extending into said tubular plug, an actuating member for said vibratory electrode, and a pawl connected with said actuating member
- 15 located in the path of the piston-stem, whereby the piston serves during its outward movement to move said actuating member through the medium of said pawl, the pawl being so arranged with relation to the piston-stem as to be released to permit said actuating member to return to its normal position when the piston reaches the outer end of its traverse.
- 20 2. The combination of a tubular plug adapted for connection with an engine-cylinder and serving as a fixed electrode, a cylinder mounted on said plug and having its inner end in communication with the interior thereof, a piston in said cylinder having a stem projecting beyond the outer end of the cylinder, a vibratory electrode extending into said plug, a pivoted rock-arm serving to actuate said electrode, a spring-held pawl mounted on said rock-arm and normally located in the path of the piston-stem, and means for limiting the movement of said pawl under the action of its spring, whereby the pawl is released from the piston-stem as the piston reaches the outer end of its traverse, for the purpose set forth.
- 25 3. The combination of a tubular plug adapted for connection with an engine-cylinder and constituting a fixed electrode, a cylinder mounted upon said plug and in communication with the interior thereof, a piston movable in said cylinder having a stem projecting beyond the outer end of the cylinder, a vibratory electrode extending into the tubular plug, a rock-arm serving to actuate said electrode in one direction, yielding means tending normally to close the vibratory electrode and to hold said rock-arm in its normal position of rest, a pawl connected with said rock-arm and located normally in the path of the piston-stem, and a spring-held lever having a bearing on the piston-stem and tending to hold the piston at the inner end of its traverse.
- 40 4. The combination of a tubular plug adapted for connection with an engine-cylinder

and serving as a fixed electrode, a cylinder mounted thereon and in communication with the interior thereof, a piston in said cylinder having a stem projecting beyond the outer end of the cylinder, a vibratory electrode extending into said plug, an actuating member for said vibratory electrode, spring connection between said actuating member and said vibratory electrode tending normally to move the electrode to the closed position and to move said actuating member to its normal position of rest, a spring-held pawl mounted on said actuating member and located normally in the path of the piston-stem, and a spring-held member having a bearing on the outer end of the piston-stem and tending to hold the piston at the inner end of its traverse.

5. The combination of a tubular plug adapted for connection with an engine-cylinder and constituting a fixed electrode, a disk insulatingly mounted on said plug and having a perforation therein, a vibratory electrode extending through said perforation, a cylinder mounted on said disk having its inner end in communication with the interior of said tubular plug, a piston in said cylinder having a stem projecting beyond the outer end of the cylinder, a standard mounted on said disk opposite said cylinder, a rock-arm pivoted on said standard and having cam connection with said vibratory electrode, a spring-held pawl pivoted on said rock-arm and located normally in the path of said piston-stem, and a spring-held member having a bearing on the piston-stem and tending to hold the piston at the inner end of its traverse, for the purpose set forth.

6. The combination with a tubular plug adapted for connection with an engine-cylinder and constituting a fixed electrode, a disk insulatingly mounted on said plug and equipped with a cylinder having its inner end in communication with the interior of said plug, a piston in said last-named cylinder equipped with a piston stem, a vibratory electrode extending through said disk, a rock-arm support opposite said cylinder, a rock-arm pivoted on said support and having spring connection and cam connection with the outer end of said vibratory electrode, a spring-held pawl mounted on said rock-arm and located normally in the path of the piston-stem, and a spring-held member having a bearing on the piston-stem and tending to hold the piston at the inner end of its traverse.

7. The combination with a tubular plug adapted for connection with an engine-cylinder and constituting a fixed electrode, of a cylinder mounted thereon and having its inner end in communication with the interior thereof, a piston mounted in said cylinder, a vibratory electrode located at one side of said cylinder and extending into said plug, a sup-

- 45 5. The combination with a tubular plug adapted for connection with an engine-cylinder and constituting a fixed electrode, of a cylinder mounted thereon and having its inner end in communication with the interior thereof, a piston mounted in said cylinder, a vibratory electrode located at one side of said cylinder and extending into said plug, a sup-

port on the other side of said vibratory electrode, a rock-arm pivoted on said support and having cam connection with the outer end of said vibratory electrode, means tending to move the vibratory electrode to the closed position and to maintain said rock-arm in its normal position of rest, a spring-held pawl pivoted on said rock-arm and adapted to be actuated by the piston and thereby to lift said rock-arm to permit the vibratory electrode to move to the closed position, said pawl adapted to be released as the piston nears the outer end of its traverse, and a spring serving to return the piston to the inner end of its traverse.

8. The combination of a tubular plug, a cylinder mounted thereon and in communication with the interior thereof, a vibratory electrode extending into the plug and having its outer end provided with a cam-surface, a pivoted rock-arm, an adjustable member carried thereby and serving to engage said cam-surface, yielding means tending to move said vibratory electrode to the closed position and to maintain said rock-arm in its normal position of rest, and a spring-held pawl mounted on said rock-arm and adapted to be actuated by the piston and thereby actuate said rock-arm, for the purpose set forth.

30 9. The combination of a tubular plug, a cylinder mounted thereon and in communication with the interior thereof, a piston movable in said cylinder, a vibratory electrode extending into said plug and equipped at its outer end with a cam-surface, a pivoted rock-arm, an adjustable member carried thereby and coacting with said cam-surface, a spring connecting said adjustable member with said vibratory electrode, a spring-held pawl carried by said rock-arm and adapted to be actuated by the piston, and a spring tending to hold the piston at the inner end of its traverse.

10. The combination of a tubular plug, a disk insulatingly mounted thereon and equipped near one edge with a cylinder and near the opposite edge with a standard, a piston in said cylinder having a stem projecting beyond the outer end of the cylinder, a vibratory electrode extending through said disk and into said plug, a spring-held lever having a bearing on said plug and having a pivotal portion journaled in said standard, a rock-arm supported on the pivotal portion of said lever and having cam connection with said vibratory electrode, and a spring-held pawl mounted on said rock-arm and located normally in the path of the piston-stem.

11. The combination of a tubular plug, a disk mounted thereon and equipped near one edge with a cylinder and near the opposite edge with a standard, a piston in said cylinder having a stem projecting beyond the end of the cylinder, a vibratory electrode extending through said disk between the cylinder

and standard, a rock-arm serving to actuate the vibratory electrode, a spring-held pawl mounted on said rock-arm, and a spring-held lever having a pivotal portion journaled in said standard and serving as a bearing for 70 said rock-arm, said lever having an arm bearing upon the piston-stem and affording a stop for said pawl.

12. The combination of a tubular plug, a disk insulatingly mounted thereon and 75 equipped near one edge with a cylinder and near the opposite edge with a standard, a piston in said cylinder having a stem projecting beyond the outer end of the cylinder, a vibratory electrode extending through said disk 80 and having its outer end located between said cylinder and standard, a rock-arm having cam connection with said vibratory electrode and bearing normally against the outer end of said cylinder, a spring connecting said 85 rock-arm with said vibratory electrode, a pawl pivoted on said rock-arm and located normally in the path of the piston-stem, a spring connecting said pawl with said rock-arm, and a spring-held lever having a pivotal 90 portion journaled in said standard and affording a support for said rock-arm and having another portion bearing upon the outer end of the piston-stem and affording a stop for said pawl.

95 13. The combination with a tubular plug adapted for connection with an engine-cylinder and constituting a fixed electrode, of a member insulatingly mounted thereon equipped with a cylinder whose inner end is in 100 communication with the interior of said plug, a piston in said cylinder, a vibratory electrode extending through said member and having a bearing in said member, a spring connected with the vibratory electrode and 105 serving to maintain a close joint at said bearing, and piston-actuated electrode-actuating means, for the purpose set forth.

14. The combination of a tubular plug adapted for connection with an engine-cylinder, a cylinder mounted thereon having a port in communication with the interior of said plug, means for regulating the passage of gas through said port, a movable electrode extending into the plug, and gas-actuated 110 electrode-actuating means, for the purpose 115 set forth.

15. The combination of a tubular plug adapted for connection with an engine-cylinder, a cylinder mounted thereon having 120 a port in communication with the interior of said plug, means for regulating the passage of gas through said port, a movable electrode extending into the plug, and gas-actuated 125 spring-retracted electrode-actuating means, for the purpose set forth.

16. In a device of the character set forth, the combination of a tubular plug adapted for connection with an engine-cylinder, a member carried thereby provided with a 130

- bearing, a vibratory electrode extending through said member and into the plug and having a coacting bearing, a spring outside of said member and connected with the vibratory electrode and serving to maintain a close joint, and gas-actuated means coacting with the outer end of the vibratory electrode and serving to actuate said electrode.
- 10 17. In a device of the character set forth, the combination of a plug adapted for connection with an engine-cylinder, a cylinder carried thereby and communicating through the plug with the engine-cylinder, a piston movable in said cylinder, a movable electrode, a spring tending to move said electrode to the closed position, a cam holding said electrode normally in the open position, and releasable piston-actuated means serving in the outward movement of the piston to move said cam and permit the spring to move said electrode to the closed position and serving also, upon release from the piston, to return the cam to the normal position and thereby return the electrode to the open position.
- 15 18. In a device of the character set forth, the combination of a plug adapted for connection with an engine-cylinder, a cylinder carried thereby and communicating through the plug with the engine-cylinder, a piston movable in said cylinder, a spring-held movable electrode tending to move to the closed position, and releasable spring-held electrode
- actuating means actuated by said piston normally holding the electrode in the open position against the action of its spring, said piston serving in its outward movement to release said electrode from its restraint to permit it to move to the closed position and said electrode-actuating means serving, upon release from the piston, to return the electrode to the open position against the action of its spring.
- 20 19. In a device of the character set forth, the combination of a plug adapted for connection with an engine-cylinder, a movable electrode, a cylinder communicating through the plug with the engine-cylinder, gas-actuated electrode-actuating means in said cylinder, and an adjustable valve controlling the passage from the engine-cylinder to said second-named cylinder.
- 25 20. The combination of a plug adapted for connection with an engine-cylinder, a cylinder carried thereby and communicating with the engine-cylinder, a piston having a stem projecting through the outer end of said cylinder, a valve-seat in the cylinder, a coacting valve-surface on the piston, a movable electrode, and electrode-actuating means actuated by the piston-stem, for the purpose set forth.
